SEWING MACHINE ATTACHMENT OR
ACCESSORYFrank W. Merrick, Dorchester, Mass., assignor
to American Stay Company, East Boston, Mass.,
a corporation of Massachusetts

Application July 11, 1931, Serial No. 550,085

19 Claims. (Cl. 112—152)

My invention relates to a sewing machine attachment or accessory, particularly adapted for use for stitching vamps to quarters of shoe uppers with a piping between the two at the edge 5 of the vamp, and for use in like situations.

The invention will be best understood from the following description when read in the light of the accompanying drawings of an embodiment of the invention selected for illustrative purposes, while the scope of the invention will be more particularly pointed out in the appended 10 claims.

In the drawings:

Fig. 1 is a plan of the attachment or accessory 15 in assembled relation with the sewing machine, the figure corresponding to a section on the line 1—1 of Fig. 2;

Fig. 2 is an elevation according to Fig. 1, with parts in section, showing a fragment of the head 20 of the sewing machine;

Fig. 3 is a section on the line 3—3 of Fig. 1;

Fig. 4 is a plan, on an enlarged scale, of the 25 parts of the attachment or accessory adjacent the needle, showing the work in position;

Figs. 5, 6 and 7 are respectively sections on the 30 lines 5—5, 6—6 and 7—7 of Fig. 4;

Fig. 8 is a section on the line 8—8 of Fig. 1, with parts in elevation, and the guide means for the piping and vamp edge omitted;

Fig. 9 is an end elevation on an enlarged scale 35 of the portion of the guide for the piping and vamp adjacent the needle as viewed from the left in Fig. 1;

Fig. 10 is a plan on an enlarged scale of the 40 parts adjacent the needle with the reciprocating presser-foot omitted;

Fig. 11 is a view corresponding to Fig. 10 with the member carrying the vamp guide omitted; and

Fig. 12 is a diagram of the parts adjacent the 45 needle, showing the areas contacted by the two presser-feet.

In attaching the vamps to quarters of shoes it 50 is desirable for purposes of ornamentation and for strengthening the seam to insert a piping, welt, or the like, this construction being indicated in Fig. 4 in which the vamp is indicated at 1, the quarter at 3, and the piping at 5. The piping shown consists of a narrow folded ribbon of leather, and is inserted between the vamp and quarter with its edge 7 projecting slightly beyond the edge 9 of the vamp. It will be understood, however, that the invention is not limited to this particular use, and that the terms "vamp," 55 "quarter" and "piping" are used herein and in

the appended claims only in an illustrative sense. It will also be understood that the attachment may be used to apply piping-welt or the like to a single sheet of material.

As illustrated, the attachment or accessory 5 comprises a plate-like member 11 having a portion 13 adapted to be substituted for the usual bobbin plate or cover of a sewing machine, the latter, as herein shown, comprising a base 15 carried by a bench 16 which base has a slot 17 10 for receiving the bobbin plate. Herein, the portion 13 is secured to the sewing machine base by a clamping bar 19 which engages the under side of the base adjacent the edges of the slot 17, the clamping action being secured by a screw 21 15 the head of which is exposed at the upper side of the portion 13 of the plate-like member 11.

As illustrated, the plate-like member 11 has an offset portion 23 provided with the upstanding ears 25, which latter have screw threaded 20 perforations for receiving pivot pins 27 for hingedly supporting a flat leaf-like or plate-like member which serves as a guide for the piping and the vamp edge. As shown, the last mentioned member has a base portion 29 cooperat- 25 ing with the pivot pins 27. On its upper face the base portion 29 is formed with a longitudinally extending slot 31 in which is slidably received the portion 33 of the guide member, which portion is formed with a transverse arm 35 ex- 30 tending to adjacent the needle 37.

As shown, for supporting the free end of the arm 11, the latter screw-threadedly carries a post 38 adapted to rest at its lower end on the top of the bench 16. Herein, the arm 35 of the 35 guide member is formed on its upper surface with a groove 39, the arm having on its upper side a plate 41 which covers the groove so as to provide a covered passage for guiding the piping to the needle. As shown, the plate 41 is notched as indicated at 43, the exposed portion of the groove 39 adjacent the notch, as viewed in Fig. 1, serving as an opening for entrance of the piping to the passage afforded by the groove. Herein, the plate 41 is provided on its end with a pin 45 shown as positioned directly opposite the needle, this pin serving to gauge the distance the piping projects beyond the edge of the vamp, which latter contacts the pin and is guided thereby during the sewing operation.

For adjusting the pin 45 relative to the groove 39 for guiding the piping, the plate 41 which carries the pin is pivotally connected to the arm 35 by a pin 47. For turning the plate 41 about its pivot, the plate 33 rotatably carries an eccentric 55

pin 49, opposite sides of which latter are contacted by the side walls of a notch 51 formed in the end of the plate 41. As best illustrated in Figs. 1, 4 and 6, the eccentric 49 is provided with 5 an extension 53 rotatably received in a perforation 55 in the arm 35, the end of the pin 53 being provided with a head 57 for preventing its removal from the perforation. Conveniently the eccentric is provided with a slot 59 for receiving 10 the end of a screw-driver for adjusting the eccentric, the latter being held in adjusted position by the frictional fit of the parts.

Referring to Figs. 9, 10 and 11, the end of the arm 35 adjacent the needle is beveled, as indicated at 61, on its under side to approximately 15 a knife edge, the beveled portion cutting entirely through the bottom wall of the groove 39 adjacent the end of the arm to provide a pair of projections 63 leading to adjacent the needle 37 and serving to guide the piping thereto. The upper side of the plate 41 adjacent the needle is beveled, as indicated at 65, at one side of its top 20 surface to a knife edge indicated at 67. This construction provides a minimum thickness of 25 metal between the layers of the work being sewed, and facilitates proper holding of the work when operated upon by the presser-feet hereinafter described.

Although the invention is applicable to various 30 types of sewing machines, that herein indicated comprises a needle bar 69 and a pair of presser-foot bars 71, 73, below which is a work feed 75. The mechanism of the sewing machine, which it is believed unnecessary to describe, and which, 35 for example, may be the well known Singer 108 W. 1, operates to cause the needle bar and presser-foot bar 71 to be reciprocated and "walked" with the feed 75 so as to advance the work the 40 distance of a stitch for each reciprocation of the needle, the presser-foot bar 73 being of the plain reciprocating type, acting to hold the work except when the needle bar and presser-foot bar 71 are "walked."

As shown, the walking presser-foot 76 on the 45 end of the bar 71 has a lower work engaging portion 77 provided at its front with a groove 79 the walls of which are closely adjacent to the needle. The presser-foot 81 on the presser-foot bar 73, as illustrated, has a portion 83 in front of the 50 needle and a side portion 85 which contacts with the side of the lower portion 77 of the presser-foot 76 so as better to maintain the two presser-feet in operative relation with each other and the needle. The portion 83 of the reciprocating 55 presser-foot 81 is beveled at its front and sides to clear the ends of the projections 63 on the ends of the arm 35 and to contact with the work in the space between these projections, the contact area being approximately indicated by the 60 dotted line surface area 87 in Fig. 12, which latter shows a diagrammatic arrangement of the parts. The remaining bottom area of the presser-foot 81 is so formed as to clear the work or at least to contact with it with a minimum of pressure. The contact area of the walking presser-foot 76 carried by the presser bar 71 is indicated 65 in Fig. 12 approximately by the dotted line surface area 91.

As a result of the above described construction, 70 it will be observed that the work is held at both sides of the needle when the latter penetrates the work, and is held by the portion 77 of the walking presser-foot 76 during the feeding operation. It will be further observed that herein 75 the piping is guided approximately all the way

to the needle, and that the pin 45 for gauging the vamp edge, being located directly opposite the needle, permits the operator readily to swing the work where the edge of the vamp is an irregular line as commonly found in shoes.

In practice, the two presser-feet and needle may be raised by the usual lever operated mechanism commonly provided for this purpose in sewing machines, which permits the end of arm 35 adjacent the needle to be lifted slightly to enable 10 the quarter to be inserted under the arm and the vamp to be placed on top of the arm, after which the presser-feet may be released to contact with the work. The proper adjustment of the parts relative to the needle may be secured 15 by use of the screw-threaded pins 27, which are effective to adjust the parts transversely of the sewing machine bed as viewed in Fig. 1, and also by sliding the plate 33 in the groove 31 for adjusting the parts longitudinally of said bed, while 20 the distance the piping projects beyond the vamp edge may be adjusted by use of the eccentric 49. For the above purpose the part 33 may be adjustably secured to the part 29 in any convenient manner, as for example by providing the part 33 with slots 93 through which extend headed 25 clamping screws 95 threaded into the part 29.

It will be observed that the present invention provides for application of the attachment or accessory without change in the sewing machine, 30 for the reason that the base 13 is substituted for the usual bobbin plate, and the two presser-feet of course attached to the presser bars in the ordinary manner so as to be interchangeable with other presser-feet used with the sewing machine. 35 This enables the attachment to be sold as an article of commerce to shoe and leather manufacturers without it being necessary for the latter to form attaching holes in the sewing machine parts or to send the sewing machine to a 40 machine shop or the like for this purpose.

It will be understood that wide deviations may be made from the embodiment of the invention herein described without departing from the spirit of the invention.

I claim:

1. A sewing machine accessory having, in combination, guide means for directing piping or the like to the needle, a gauge means for the edge of the sheet to which said piping is stitched, said gauge means being positioned adjacent the needle and being formed to permit swinging of said sheet in opposite directions in a plane transverse to the needle during the sewing operation while said edge of said sheet is in contact therewith, and means for adjusting said gauge means relative to said guide means whereby the distance said piping projects beyond said edge of said sheet may be varied.

2. A sewing machine accessory having, in combination, guide means for directing piping or the like to the needle, a gauge means for the edge of the sheet to which said piping is stitched, and means for adjusting said gauge means relative to said guide means, whereby the distance said piping projects beyond said edge of said sheet may be varied, and for simultaneously adjusting both said gauge means and guide means relative to the needle.

3. A sewing machine accessory having, in combination, guide means for directing piping or the like to the needle, a gauge means for the edge of the sheet to which said piping is stitched, said gauge means being positioned adjacent the needle and being formed to permit swinging of said sheet

in opposite directions in a plane transverse to the needle during the sewing operation while said edge of said sheet is in contact therewith, and means for adjusting said guide means and gauge means independently of each other relative to the needle whereby the distance said piping projects beyond said edge of said sheet and the relation of the line of stitching to said piping may be varied.

10. 4. A sewing machine accessory having, in combination, guide means for directing piping or the like to the needle, a gauge means for the edge of the sheet to which said piping is stitched, said gauge means being positioned adjacent the needle and being formed to permit swinging of said sheet in opposite directions in a plane transverse to the needle during the sewing operation while said edge of said sheet is in contact therewith, and means for adjusting said guide means relative to the needle in all directions in a plane transverse to the needle and for independently adjusting said gauge means relative to said guide means in said plane.

25. 5. A sewing machine accessory having, in combination, guide means adapted to be positioned between a vamp and quarter or the like for directing piping or the like to a needle for stitching said vamp, quarter and piping, and a relatively adjustable gauge means for the vamp edge carried by said guide means, said gauge means being positioned adjacent the needle and being formed to permit swinging of said vamp and quarter in opposite directions in a plane transverse to the needle during the sewing operation while said vamp edge is in contact therewith.

30. 6. A sewing machine accessory having, in combination, guide means adapted to be positioned between a vamp and quarter or the like for directing piping or the like to a needle for stitching said vamp, quarter and piping, and gauge means for the vamp edge carried by said guide means positioned approximately directly opposite said needle, said gauge means being so formed as to permit swinging of said vamp and quarter in opposite directions in a plane transverse to the needle during the sewing operation while said vamp edge is in contact therewith.

35. 7. A sewing machine accessory having, in combination, guide means adapted to be positioned between a vamp and quarter or the like for directing piping or the like to a needle for stitching said vamp, quarter and piping, gauge means for the vamp edge, said gauge means being positioned adjacent the needle and being formed to permit swinging of said vamp and quarter in opposite directions in a plane transverse to the needle during the sewing operation while said vamp edge is in contact therewith, and presser-foot means for engaging the work in front and in back of the needle at points closely adjacent thereto.

40. 8. A sewing machine accessory having, in combination, guide means adapted to be positioned between a vamp and quarter or the like for directing piping or the like to a needle for stitching said vamp, quarter and piping, gauge means for the vamp edge positioned approximately directly opposite the needle, and presser-foot means for engaging the work in front and in back of the needle at points closely adjacent thereto.

45. 9. A sewing machine accessory having, in combination, guide means adapted to be positioned between a vamp and quarter or the like for directing piping or the like to a needle for stitching said vamp, quarter and piping, relatively ad-

justable gauge means for the vamp edge positioned approximately directly opposite the needle, and presser-foot means for engaging the work in front and in back of the needle at points closely adjacent thereto.

50. 10. A sewing machine accessory having, in combination, guide means terminating adjacent the needle adapted to be positioned between a vamp and quarter or the like to the needle, the latter for stitching said vamp, quarter and piping, a vamp edge guide, a so-called walking-presser-foot for engaging the work behind the needle at points adjacent the latter, and a presser-foot for engaging the work adjacent the end of said guide means.

15. 11. A sewing machine accessory having, in combination, guide means terminating adjacent the needle adapted to be positioned between a vamp and quarter or the like for directing piping or the like to the needle, the latter for stitching said vamp, quarter and piping, a vamp edge guide approximately directly opposite the needle, a so-called walking-presser-foot for engaging the work behind the needle at points adjacent the latter, and a presser-foot for engaging the work in front of the needle adjacent the end of said guide means.

20. 12. A sewing machine accessory having, in combination, guide means terminating adjacent the needle adapted to be positioned between a vamp and quarter or the like for directing piping or the like to the needle, the latter for stitching said vamp, quarter and piping, a vamp edge guide, a so-called walking-presser-foot for engaging the work adjacent the needle, and presser-foot means for engaging the work behind said walking-presser-foot and in front of the latter adjacent the end of said guide means.

25. 13. A sewing machine accessory having, in combination, guide means terminating adjacent the needle adapted to be positioned between a vamp and quarter or the like for directing piping or the like to the needle, the latter for stitching said vamp, quarter and piping, a vamp edge guide approximately directly opposite the needle, a so-called walking-presser-foot for engaging the work adjacent the needle, and presser-foot means for engaging the work behind said walking-presser-foot and in front of the latter adjacent the end of said guide means.

30. 14. A sewing machine accessory having, in combination, guide means terminating close to the needle adapted to be positioned between a vamp and quarter or the like for directing piping or the like to the needle, the latter for stitching said vamp, quarter and piping, an adjustable vamp edge guide, a so-called walking-presser-foot for engaging the work adjacent the needle, and a presser-foot having portions for engaging the work at opposite sides of the needle and at opposite sides of said walking-presser-foot.

35. 15. A sewing machine accessory having, in combination, a flat leaf-like device adapted to be positioned between a vamp and quarter or the like having guide means for directing piping or the like to the needle, the latter for stitching said vamp, quarter and piping, said device having a vamp edge guide.

40. 16. A sewing machine accessory having, in combination, a flat leaf-like device adapted to be positioned between a vamp and quarter or the like having guide means for directing piping or the like to the needle, the latter for stitching said vamp, quarter and piping, said device having an adjustable vamp edge guide.

17. A sewing machine accessory having, in combination, a flat leaf-like device adapted to be positioned between a vamp and quarter or the like having guide means for directing piping or the like to the needle, the latter for stitching said vamp, quarter and piping, said device having a vamp edge guide and a hinged support for said device.
18. A sewing machine accessory having, in combination, a flat leaf-like device adapted to be positioned between a vamp and quarter or the like having guide means for directing piping or the like to the needle, the latter for stitching said vamp, quarter and piping, said device having a vamp edge guide and an elongated plate-like member adapted to be substituted for the bobbin
- 5 cover of the sewing machine, said device having a hinged connection to said plate-like member.
19. A sewing machine accessory having, in combination, an extensible flat leaf-like device adapted to be positioned between a vamp and quarter or the like having guide means for directing piping or the like to the needle, the latter for stitching said vamp, quarter and piping, said device having a vamp edge guide adjacent the needle mounted for adjustment transversely of the direction in which the work is fed, a supporting member hingedly connected to the end of said device, and means for adjusting said device transversely of said supporting member.
- 5 10 15
